HOUSING FOR AN ELECTRO HYDRAULIC REGULATOR

Alfred Weis, Olpe, Westphalia, Germany, assignor to
Elektro-Mechanik G.m.b.H., Olpe, Westphalia, Germany

Filed Oct. 5, 1959, Ser. No. 57,814

Claims priority, application Germany Apr. 9, 1959

Term of patent 14 years

(Cl. D26—5)

Fig. 2

Fig.3

Fig.4

FIG. 1 is an elevation of a housing for an electro hydraulic regulator showing my new design;

FIG. 2 is a top plan view thereof;

FIG. 3 is an elevation thereof as seen from the left of FIG. 1; and

FIG. 4 is an elevation thereof as seen from the opposite side of FIG. 1.

I claim:

The ornamental design for a housing for an electro hydraulic regulator, as shown.
